UNITED STATES PATENT OFFICE.

EDWARD ZUVER LEWIS, OF FRANKLIN, PENNSYLVANIA, ASSIGNOR TO THE GENERAL MANIFOLD AND PRINTING COMPANY, OF FRANKLIN, PENNSYLVANIA, A CORPORATION OF PENNSYLVANIA.

SALES-CHECK.

972,549.

Specification of Letters Patent. Patented Oct. 11, 1910.

Application filed February 28, 1908. Serial No. 418,208.

To all whom it may concern:

Be it known that I, EDWARD ZUVER LEWIS, a citizen of the United States, and a resident of Franklin, in the county of Venango 5 and State of Pennsylvania, have invented certain new and useful Improvements in Sales-Checks; and I do hereby declare that the following is a full, clear, and exact description thereof, reference being had to the 10 accompanying drawings, and to the letters of reference marked thereon, which form a part of this specification.

This invention relates to duplex sales checks, such as are used in restaurants and 15 like establishments and which include two connected sheets, one of which constitutes a customer's check and the other a waiter's check, and transfer means interposed between the sheets by which carbon copies of 20 the items written on the superposed sheet are made upon the lower sheet, which constitutes the customer's check; the superposed sheet being intended to be separated from the customer's check by the waiter and 25 used by the latter as an order or waiter's check in obtaining from the kitchen or other department the articles ordered.

My invention embraces improvements in a duplex check of the kind hereinbefore referred to, whereby the superposed sheet, or 30 that on which the items of the order are directly written, consists of a plurality of detachable sections or coupons on which items of different classes, or which are to be obtained from different departments of the 35 same establishment, may be separately written, and which may be detached and delivered to the different departments as orders for the articles called for, while at the same 40 time all of the items entered on the different sections or coupons will appear upon the customer's check.

The invention consists in the matters hereinafter described and pointed out in the appended claim.

As shown in the accompanying drawings:—Figure 1 is a perspective view of the duplex check embodying my invention. Fig. 2 is a face view of the sheet constituting the 50 customer's check. Fig. 3 is a face view of the sheet constituting the waiter's coupons before the same is attached to the customer's check. Fig. 4 is a cross-section of the two connected sheets forming the duplex check.

55 As shown in said drawings, 5 indicates a

sheet which constitutes the customer's check and which is preferably made of relatively stiff paper or cardboard.

6 indicates the waiter's check sheet which is preferably made of thin paper and which 60 is provided on its back surface with a coating of carbon or other transfer material whereby any writing upon the said sheet will be transferred to the customer's check.

The two sheets 5 and 6 are connected with 65 each other at one of the side or lateral edges of the duplex check in any suitable manner, permitting the same to be readily separated from each other. As illustrated, the check sheet is provided at one of its side edges 70 with a laterally extending strip 7 separated from the body of the sheet by a line of perforations 8, and adapted to be pasted to the under surface of the side margin of the customer's check sheet 5, as clearly seen in 75 Fig. 4.

The waiter's check sheet 6 is provided with a plurality of transversely extending perforated lines 9 and 10 extending from the free lateral margin thereof to the perforated 80 line 8, and dividing the said sheet into a plurality of detachable check slips or coupons 11, 12 and 13. The customer's check sheet 5 is without any perforated lines but is preferably provided with transverse 85 printed lines or otherwise marked to indicate a plurality of transversely extending spaces 14, 15 and 16, corresponding with the sections or coupons of the waiter's check sheet. The customer's check sheet will have 90 at the right hand side margin thereof a vertically arranged space 17 extending substantially the full length of the sheet and in which the amounts charged for the several items appearing on the sheet may be entered 95 in a single column. The two sheets will bear a common designating character or number which, in the case of the superposed or waiter's check sheet 6, will also be applied to each of the sections or coupons 11, 100 12 and 13 thereof.

From the construction described, it will be manifest that either of the sections or coupons 11, 12 and 13 of the waiter's check sheet 6 may be detached from the said sheet, 105 and from the customer's check by tearing or dividing the said sheet along one of the transverse lines 9 or 10 and also along the line 8, and that one or more of said sections or coupons may be detached at a time as de- 110

sired, leaving one or more of the said checks or coupons attached to the customer's check.

In the use of the duplex check made as described, the items constituting the principal part of an order, such as those calling for articles to be obtained from the kitchen, will be entered in the space at the upper or main part of the check, constituting the coupon 11, and which will usually be made 10 long enough to contain a considerable number of items. Items constituting an order going to another department as, for instance, to the bar, will be entered at the same time or later upon the lower coupon 13. Items constituting later orders for the same or other departments may be entered 15 on the coupon 12. As the entry of each item is made a coupon or transfer duplicate of the entry will be made upon the main or 20 customer's check 5 and on this check the charges for all of the items will be entered and the same delivered to the customer to 25 be handed to the cashier when paying the check. The waiter in obtaining the articles 30 ordered will separate the coupons from the customer's check as needed, delivering one check to the kitchen and other sections to other departments, or to the same department in the case of additional or later 35 orders for articles of the same class as previously ordered by the same customer.

The duplex check made as described 40 serves to enable the proprietor of an establishment to keep a check upon articles furnished to customers from different departments of the establishment; it being manifest that, by comparing the several items on the separate waiter's check coupons in the hands of different supply departments with 45 the customer's check in the hands of the cashier, the proprietor may ascertain that all of the articles furnished by the different departments were properly entered upon the customer's check and paid for by the latter.

In the accompanying drawings, a duplex check is shown in which the superposed or waiter's check sheet is divided into three

coupons only by two perforated lines, but it will be understood that such superposed 50 check sheets may be transversely divided into any desired number of coupons, thereby providing for orders from a number of different departments and for a number of orders given at different times by the same 55 customer, all of which will be recorded on one customer's check. While the superposed or waiter's check sheet 6 is shown as provided with a line of perforations 8, permitting the easy detachment of the individual 60 sections of coupons from the customer's check, yet the presence of such a line of perforations is not essential, especially where the customer's check is made of relatively thick 65 or stiff paper, inasmuch as the separate sections may, in such a case, be readily detached or torn along the line of junction between the sheets, without the presence of the said perforated line 8.

I claim as my invention:—

A duplex sales check consisting of a customer's check-sheet of relatively stiff paper or cardboard, and a waiter's order-sheet of greater width than said customer's check, having one margin folded beneath and secured to the lower marginal surface of said customer's check, the waiter's or uppermost sheet being provided with transversely extending perforated lines forming a plurality of detachable order slips or coupons, and the 70 customer's or lowermost sheet and all of the waiter's order slips or coupons bearing a common identifying mark or number, combined with transfer-means applied to the rear face of said waiter's order sheet acting 75 to produce on the customer's check sheet a copy of all items entered on said detachable order sheet and its slips or coupons.

In testimony that I claim the foregoing 80 as my invention I affix my signature in the 85 presence of two witnesses, this 21st day of February A. D. 1908.

EDWARD ZUVER LEWIS.
